UNITED STATES PATENT OFFICE.

GEORGE A. GLAHN, OF WALLINGFORD, CONNECTICUT, ASSIGNOR TO THE SIMPSON, HALL, MILLER & COMPANY, OF SAME PLACE.

DESIGN FOR A PLATE.

SPECIFICATION forming part of Design No. 22,602, dated July 11, 1893.

Application filed April 21, 1893. Serial No. 471,349. Term of patent 3½ years.

To all whom it may concern:

Be it known that I, GEORGE A. GLAHN, of Wallingford, in the county of New Haven and State of Connecticut, have invented a new Design for Plates; and I do hereby declare the following, when taken in connection with accompanying drawings and the letters of reference marked thereon, to be a full, clear, and exact description of the same, and which said drawings constitute part of this specification, and represent, in—

This invention relates to a design for plates, and the design consists in the configuration and ornamentation as hereinafter described and shown in the accompanying illustrations.

The border A, of the plate is composed of a rich combination of scrolls, leaf-forms, and flowers, arranged to include three small blank spaces B B B. This border forms an indented or irregular edge for the plate. The center of the plate is occupied by a field C, formed by a ribbon D, and a small shield E, flanked on either side by scrolls or leaf-forms F F, 25 the said field containing a bust of Christopher Columbus. Located below the bust of Columbus is a shield E. The body of the plate between the field C, and the border A, is divided into three panels G, by as many rich radial bands H, composed of scrolls and flowers, and extending between the border A, and the ribbon D, and shield E. It is designed that the said panels shall be occupied by representations of different buildings of the World's 35 Columbian Exposition. The ornamentation and configuration of the plate are of that style of decoration known as rococo.

I claim—

The design for a plate, as herein shown and 40 described.

In testimony whereof I have signed this specification in the presence of two subscribing witnesses.

GEO. A. GLAHN.
